Inventor:

Henry Marcheter

UNITED STATES PATENT OFFICE.

HENRY MARCHETER, OF WALLACEBURG, ONTARIO, CANADA.

CAR-COUPING.

SPECIFICATION forming part of Letters Patent No. 257,878, dated May 16, 1882.

Application filed February 20, 1882. (No model.)

To all whom it may concern:

Be it known that I, HENRY MARCHETER, of the village of Wallaceburg, in the county of Kent, Province of Ontario and Dominion of Canada, have invented a certain new and useful Improvement in Car-Couplers; and I do hereby declare that the following is a full, clear, and exact description of the construction and operation of the same, reference being had to the accompanying drawings, in which—

Figure 1 is a section of the machine with the side cap or lid removed from the box or block, showing the internal appearance before the link enters the mouth of the machine or coupler. Fig. 2 is also a section, the same view showing the change produced by the link K being pushed back into the machine or coupler. Fig. 3 is likewise the same section, showing the effect produced by lifting up the pin H. Fig. 4 is a perspective view of the shuttle or valve G. Fig. 5 is also a perspective view of the flanged shuttle or valve J.

My improvement relates to machines for coupling railroad cars that will be self-fasteners.

The invention consists in the construction and arrangement of parts, hereinafter more fully described and definitely claimed.

A is a box or block of iron or other suitable material, and of proper size, fastened at the end of a car as desired, and the end of this box or block is the part that strikes when the cars come together. B is the horizontal entrance or mouth. C is a horizontal chamber to allow the end of the link K to enter. D is an inclined chamber running back and up. E is also an inclined chamber running forward and up. F is a perpendicular hole, situated between the two chambers D and E, and running clean through the coupler, and in communication with all the chambers already mentioned, also is the hole in which the pin H works. G is a loose wedge-shaped valve or shuttle, working freely up and down the inclined chamber D. H is an ordinary pin, fitting the hole F loosely, and long enough to extend well through the machine. J is another valve or shuttle, with flanged sides, that works

freely up and down the inclined chamber E. 50 K is the link, that is properly adjusted to the other car, about to enter the mouth B, as seen in Fig. 1. L is a small chain, made fast to the pin H and to the body of the machine, and is adjusted not to allow the pin to be taken out 55 altogether.

My machine operates as follows: The link K enters the mouth B and strikes the shuttle G, upon which the pin H rests. The shuttle G instantly flies from under the pin and goes 60 up the chamber D, and the pin H falls through the link K, thus coupling the cars, as is seen in Fig. 2. When it is desirable to uncouple the cars the pin H is drawn upward, and when drawn up above the chamber E the shuttle J 65 slides under the pin and holds it up. Then when the cars move away from each other the link comes out of the coupler, and the link coming out lets the shuttle G slip back to its original place, as is seen in Fig. 1, and at the 70 same time the link catches on the lower pendant part of the shuttle J and sends it flying up the chamber E, causing the pin H to fall back again on top of the shuttle G to its original position, as seen in Fig. 1, and all ready 75 again to couple itself when operated upon by the link as before.

If desirable, the flanged shuttle J can be dispensed with, and the cars will couple the same; but the pin would then have to be taken clean 80 out when uncoupled, and when the link was out the pin would have to be put back again, so that it would rest on the shuttle G. It then would be in readiness for self-coupling.

Having thus described my invention, what 85 I claim herein as new is—

In a car-coupler, the combination of the chambers B, C, D, and E with the shuttles G and J, and their relation to each other as herein shown and described. 90

In witness whereof I have hereunto signed my name, in the presence of two subscribing witnesses, this 16th day of January, 1882.

HENRY MARCHETER.
